Primary Examiner — Rachel A. Voorhies*Assistant Examiner* — Benjamin D. Wannemacher(74) *Attorney, Agent, or Firm* — Che-Yang Chen; Law
Office of Michael Chen(57) **CLAIM**The ornamental design for a rivet nut tool, as shown and
described.**DESCRIPTION**FIG. 1 is a perspective view of the rivet nut tool showing my
new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated with
numeric 9 in FIG. 2.The dash-dash broken lines shown in the drawings are
included for the purpose of illustrating portions of the rivet
nut tool that form no part of the claimed design.The dot-dash broken lines of FIGS. 2 and 9 depict the limits
of the enlarged view and forms no part of the claimed
design. The dot-dash lead lines in FIG. 2 labeled 9 indicate
the area from which the enlargement in FIG. 9 is taken and
forms no part of the claimed design.**1 Claim, 9 Drawing Sheets**| (56)	References Cited
